UNITED STATES PATENT OFFICE

EDWARD ROSCOE BLACK, OF CHICAGO, ILLINOIS, ASSIGNOR TO BLACK SYSTEMS, INC.,
OF CHICAGO, ILLINOIS, A CORPORATION OF ILLINOIS

BUILDING COVERING

Application filed August 20, 1931. Serial No. 558,236.

My invention relates to building coverings.

More particularly it relates to a weather-proof covering unit, commonly termed a shingle, adapted to be arranged in vertical and horizontal overlapping series to form the outer protective and decorative covering of the roofs and side walls of buildings.

One of the objects of my invention is to provide an improved covering unit.

Another object is to provide a covering unit which may be applied in a wide variety of ways to produce a variety of different decorative effects.

Another object is to provide a covering unit whereby a wide variety of decorative effects may be produced by units of identical construction.

A further object is to cheapen the production, stocking and handling of building covering units by providing like units capable of a wide variety of different applications.

Another object is to provide a covering unit whose configuration supplies gage or relationship indicia which facilitate the proper assembly of units to produce the desired effects.

Other objects and advantages will herein-after appear.

An embodiment and several typical applications of my improved covering unit are illustrated in the accompanying drawings wherein:

Fig. 1 is a plan view of a unit embodying my invention;

Fig. 2 is a plan view of a partial assembly of units arranged to provide the conventional hexagonal exposure;

Fig. 3 is a plan view of a partial assembly of units arranged to provide another conventional type of exposure;

Fig. 4 is a plan view of a partial assembly of units arranged to present the conventional square butt exposure; and

Fig. 5 illustrates the method of cutting or forming the units from sheets of ordinarily flexible prepared roofing material.

In general my improved building unit comprises a sheet of weather-proof material formed with one end of conventional rec-

tangular configuration and with the opposite end of conventional hexagonal configuration, the enclosing angles or corners between the edges of the unit being substantially of either 90 degrees or 135 degrees and with the length and breadth of the unit being substantially equal.

As illustrated in Fig. 1, the covering unit 10 has six straight edges $a-b$, $b-c$, $c-d$, $d-e$, $e-f$, and $f-a$. The interior angles a and b are each of substantially 90 degrees while the interior angles c , d , e and f are each of substantially 135 degrees. The two edges $a-b$ and $d-e$ are parallel to each other and the edges $a-f$ and $b-c$ are parallel to each other. The spacing or distance between the sides $a-b$ and $d-e$ is substantially equal to the space or distance between the sides $a-f$ and $b-c$. Thus, in effect, the unit may be considered as cut or formed from a square by the equal removal of two of the laterally related corners thereof, as clearly shown by the dotted lines of Fig. 1. Of course, instead of cutting off and removing the corners they may be turned under the body to form a unit of the same configuration. The relative dimensions are such that the length of either edge $a-f$ or $b-c$ is equal to the length of the edge $d-e$, plus the vertical distance between the edge $d-e$ and a line joining the corners c and f , i. e., as shown in Fig. 1 either side $a-f$ or $b-c$ is equal to the side $d-e$, plus the distance between the points x and y . In laying the units the apices of the angles between the edges of the shingles and the edges themselves form gaging points or lines which may be employed to locate each unit in its proper relation to others so as to insure the production of the desired effects. The methods of thus using these gaging marks will be understood from the following explanation of the typical layouts illustrated in Figs. 2 to 4.

In assembling the units to fabricate a covering having the conventional hexagonal butt exposure illustrated in Fig. 2, a starting strip 11, preferably formed of the same material as the units, is secured in the usual manner along the lower edge of the roof or wall to be covered. Ordinary roofing nails may be used to anchor the starting strip in place. Assum-

ing that the units are to be laid from left to right, the extreme left hand unit 10 of the first or bottom horizontal course is preferably cut perpendicular to the edge $d-e$ from the angle 5 d and positioned with that cut edge registering with the left hand edge of the roof or wall. The edge $d-e$ is registered with the lower edge of the starting strip 11. The part of the unit thus removed is illustrated in dotted lines 10 at the left of Fig. 2.

The next unit 10 of the lower horizontal course is laid with its edge $d-e$ in register with the lower edge of the starting strip and is horizontally spaced from the first unit 10 15 by separating its corner c from the corner f of the unit 10 by a distance equal to the length of the edge $d-e$. This may be readily accomplished by temporarily laying the hexagonal end of an extra unit, as illustrated in 20 dotted lines in the lower left hand corner of Fig. 2, so that its corners f and c register with the lower edge of the starting strip and its edge $e-f$ lies against the edge $e-f$ of the first laid unit 10. Then when the second 25 unit 10 is laid with its edge $d-e$ registering with the lower edge of the starting strip and its edge $c-d$ registering with the edge $c-d$ of the gaging unit, the second unit of the first horizontal course is properly positioned. The 30 same procedure may be followed until all of the units of the first horizontal course are positioned. Each unit as it is laid should be anchored in place by suitable means, such as ordinary roofing nails, preferably applied in 35 locations which will be covered by the succeeding course of units to prevent exposure of metal.

In positioning the units of the second horizontal course the corners d and e of the second 40 course units 10 are registered with the corners f and c respectively of adjacent first course units. This positions the second course units in proper vertical and horizontal overlapping relation to the adjacent lower course units.

45 The third course units are laid with their corners d and e in registry with the corners f and c respectively of the second course units, the extreme left hand unit being cut to lie along the left hand edge of the area to be 50 covered as previously explained in conjunction with the left hand unit of the first course and as indicated by the dotted lines at the left hand edge of Fig. 2.

This procedure is continued until the entire 55 area is covered, the units, of course, being anchored in proper position as previously explained in connection with the first course.

The arrangement illustrated in Fig. 3 is 60 laid by first applying a starting strip 11 to the lower edge of the area to be covered. Then the first or lowermost course of units 10 is applied by registering the edge $e-f$ with the lower edge of the starting strip. The extreme left hand unit 10 of the first 65 course is cut on a line from the corner b per-

pendicular to the side $e-f$ and the edge thus cut is registered with the left edge of the area to be covered. The portion thus removed is illustrated in dotted lines along the left hand edge of Fig. 3. The next unit of the first 70 course is positioned to horizontally overlap the first unit by registering the corner c with the edge $a-b$ of the first unit and by registering its corner d with the edge $f-a$ of the first unit. Subsequent units of the first horizontal row or course are similarly registered relative to the preceding unit of the same course. Each unit as it is thus located should be anchored in place by suitable means, such as ordinary roofing nails driven there-through in locations which will subsequently be covered by succeeding units. If desired, the proper positioning of adjacent units in the first course may be facilitated by using 75 one of the right angled corners of an extra unit as shown by the dotted lines at the lower edge of Fig. 3 to insure that the angle formed by the edge $a-f$ of one unit and the edge $d-e$ of the adjacent unit is a right angle.

The units of the second horizontal course 80 are so positioned relative to the units of the first course that the corner c of each second course unit registers with the corner b of a first course unit and the corner a of the second course unit registers with the edge $a-b$ of a 85 first course unit. The proper relative positions of adjacent units in the second course are registered, like those of the first course, by horizontally overlapping the units from left to right until the overlying corner c of each unit registers with the underlying edge $a-b$ of the preceding unit and the overlying corner d of each unit registers with the underlying edge $a-f$ of the preceding unit. Subsequent courses are vertically and 90 horizontally positioned in a similar manner until the entire area is covered.

The conventional square-butt exposure arrangement illustrated in Fig. 4 is laid by 95 first placing a starting strip 11 along the lower edge of the area to be covered, in the usual way. The first horizontal course of units 10 is then located by registering the edge $a-b$ of each unit with the lower edge 100 of the starting strip, the distance between adjacent units being gaged by horizontally separating the adjacent edges until the space between equals the length of the side $d-e$. This spacing may be readily accomplished by 105 using an extra unit as indicated by the dotted lines at the lower right hand edge of Fig. 4. The edge $a-f$ of the unit at the extreme left end of the first course is registered with the left hand vertical line of the area to be 110 covered.

The second course units are laid with the 115 rectangular end down and registered relative to the first course and to each other by 120 registering their corners $c-f$ respectively 125 130

with the corners *e-d* of adjacent units of the lower course.

The units of subsequent courses are similarly positioned until the entire area is covered, each unit being anchored as previously described.

While ordinary roofing nails have been mentioned as the anchoring means for securing the units to the underlying building framework, it will be readily understood that other forms of anchorage, such as that set forth in my Patent No. 1,748,327 granted February 25, 1930 may be employed.

Fig. 5 illustrates how my improved units may be cut from a sheet of ordinary roofing material, the sheet or strip being indicated as wide enough to permit four units to be taken on the width thereof. The small triangular shaped shaded areas indicate the only waste when the units are thus produced.

Although I have illustrated and described but three typical decorative designs of roof covering which may be produced by identical units formed according to my invention, it is to be understood that a variety of other designs entailing one, two or three thicknesses of material may be produced by the same covering unit. The size of the units likewise may be varied as long as the angles and proportions heretofore described are substantially followed. Mathematical precision, however, is not required to produce practical and acceptable results but the dimensional proportions and angles prescribed should obtain within the manufacturing tolerances commonly allowed in this industry.

Applicant is aware of the fact that units having the same arrangement of interior angles as the unit herein described have been known and used for years. He is also aware that square units, i. e., having equal length and breadth, have been widely known and used for years. But he does not believe that anyone before has proposed the combination of angles and proportions, and with no other combination is it possible to lay such a variety of covering designs as those herein illustrated or to use the corners of the units as gage marks for properly locating the positions of the units in the various designs.

In the claims appended to this description the word "substantially" employed in connection with the angles and dimensional portions contemplates only such variations as are permitted by manufacturing tolerances commonly allowed in this industry.

Having thus illustrated and explained the nature and characteristics of my invention, what I claim and desire to secure by United States Letters Patent is as follows:

1. A building covering unit comprising a sheet of weather-proof material defined by six straight edges arranged to form six enclosing angles, two of said angles being of

substantially ninety degrees each and the remaining four angles being of substantially one hundred thirty-five degrees each, and the length and breadth of the unit being substantially equal.

2. A building covering unit comprising a sheet of weather-proof material with six straight edges defining an area having two substantially right angle corners and four substantially one hundred thirty-five degree corners and with the length and breadth of the area being substantially equal.

3. A building covering unit comprising a sheet of weather-proof material having six straight edges defining an area having two substantially right angle corners and four substantially one hundred thirty-five degree corners, and wherein the length and breadth of the unit are substantially equal.

In witness whereof, I hereunto subscribe my name this 10th day of August, 1931.

EDWARD ROSCOE BLACK.
